UNITED STATES PATENT OFFICE.

EDWARD WRIGHT, OF WORCESTER, MASSACHUSETTS, ASSIGNOR TO THE
WRIGHT MACHINE COMPANY, OF SAME PLACE.

GOVERNOR-VALVE.

SPECIFICATION forming part of Letters Patent No. 324,446, dated August 18, 1885.

Application filed November 20, 1884. (No model.)

To all whom it may concern:

Be it known that I, EDWARD WRIGHT, a citizen of the United States, residing at Worcester, in the county of Worcester and State of Massachusetts, have invented certain new and useful Improvements in Governor-Valves; and I declare the following to be a description of my said invention sufficiently full, clear, and exact to enable others skilled in the art to 5 to which it appertains to make and use the same, reference being had to the accompanying drawings, which form a part of this specification.

The object of my present invention is to provide a valve mechanism for governors wherein 15 the valve is coupled to its operating spindle or stem by a loose connecting-piece in a manner to allow limited lateral movement of the valve independently of its spindle while closely confined to rotate with said spindle, thereby permitting the self-adjustment of the valve in a 20 degree sufficient to obviate any cramping or binding action in case the valve-seat and spindle are not perfectly concentric and parallel with each other, and also adapting the mechanism for operating with the least possible 25 amount of friction, so that the valve can be readily and freely actuated by a light-running governor, or with the exertion of but slight force, thus producing a more sensitive and 30 quicker acting mechanism. This object I attain by the mechanism herein shown and described.

Figure 1 is a central section of a governor-valve mechanism constructed in accordance 35 with my invention. Fig. 2 is a transverse section of the same. Figs. 3 and 4 are views showing the detail of the valve-piece. Figs. 5, 6, and 7 are views showing the details of the coupling-piece, and Figs. 8 and 9 show the 40 side and end of the valve-spindle.

In referring to parts, A denotes the body, shell, or casing, which is provided with suitable passages, a a' , with bosses for attachment of the steam-pipes, and with an annular chamber, A^2 , separated from the interior or valve chamber by the cylindrical valve-seat B, having ports b leading from said annular chamber to the interior chamber.

C indicates the valve, which is formed, as 50 shown, with open ends and sides, and having

bars c , of proper number and dimensions for covering and closing the several ports b . Said valve is fitted to work freely within the seat B, and is mounted upon a central stem or spindle, E, to which it is connected by an interlocking coupling-piece, D, in a manner to permit limited lateral movement of the valve, or diametric self-adjustment, to an extent sufficient to give freedom of action within the seat, while it is confined rotatively, so as to 55 move with the action of the spindle E.

The coupling-piece D is made as shown in Figs. 5, 6, and 7, and is arranged between the valve and spindle, with its radial projections d engaging with recesses c^2 at one end of the valve 60 C, while at the opposite end the bifurcated arms d^2 of the coupling embrace the cross-head 65 e of the valve-spindle E. The radial relation of the engaging parts d c^2 and d^2 e is at right angle to each other, or nearly so. These interlocking lugs and recesses are fitted in a manner to prevent independent rotative movement between the parts, while permitting slight lateral movement, so that the valve can assume positions in a slight degree inclined or 70 eccentric to the axis of the spindle. The valve is confined longitudinally between the projections d and the ends of the cross-head e.

The valve-spindle E may be made with a long outward taper and fitted without packing 75 to work in a correspondingly long tapered bearing sleeve or bushing, F, screwed into the face-plate of the casing A, while an adjustable step or screw, H, is arranged for supporting 80 its end and adjusting it against the action of 85 steam-pressure from within, thus forming a steam-tight joint of the nature described in my Letters Patent No. 298,049.

The spindle E is connected by suitable device, I, at the exterior of the case with the reciprocating rod K, controlled by governor mechanism of any suitable construction, (such, for instance, as that described in my Letters Patent No. 283,842,) whereby the said spindle and valve are actuated for opening and closing the ports b and regulating the flow of steam 95 through the apparatus.

By constructing and arranging the valve devices as above described cramping or binding of the parts in action is obviated, and the 100

friction is reduced to an inappreciable minimum, so that the valve can be operated by a light-running sensitive governor.

What I claim as of my invention, to be secured by Letters Patent, is—

1. A valve mechanism having a cylindrical valve-seat, a central operating spindle or valve-stem, and a cylindrical valve connected with said spindle by an intermediate coupling-piece arranged substantially as set forth, whereby lateral self-adjustment of the valve is permitted, while it is rotatively confined to move with said spindle.

2. The combination, with the valve-seat B and spindle E, of the valve C and the coupling-piece D, having lugs for engaging said

valve and spindle, substantially as and for the purpose set forth.

3. The combination of the chambered casing A, provided with the valve-seat B, having ports b, the internally-tapered bushing F, the tapered spindle E, having cross-head e, the valve C, having recesses c¹, and the coupling-piece D, having projections d and recesses d¹, substantially as and for the purpose set forth.

Witness my hand this 10th day of November, A. D. 1884.

EDWARD WRIGHT.
